DOOR LOCK

Fullerton George Gordon Armstrong, Beverley,
East Yorkshire, EnglandApplication February 3, 1937, Serial No. 123,924
In Great Britain February 28, 1936

2 Claims. (Cl. 292—335)

The present invention relates to door locks and has for its object the provision of means for enabling a lock to be operated quietly and with certainty on the closing movement. Accordingly the 5 invention is particularly applicable to doors for automobiles and other vehicles.

According to the present invention and from one aspect thereof a resiliently loaded trip mechanism is disposed in the path of movement of a 10 resiliently loaded lock bolt to limit its displacement in the locking direction from the fully retracted to the fully projected position until the trip mechanism is released.

It will thus be seen that after opening of a 15 door to which a lock of the present invention is attached the release of the handle in operative engagement with the bolt enables the latter under the action of its resilient load to move automatically from the fully retracted position 20 to a partially retracted position ready for the succeeding act of closing the door, whereby only the release of the bolt from the partially retracted position to the fully projected position is required to complete the closing. The release of 25 the trip mechanism is effected preferably by the act of commencing the final movement of closing, that is to say it is automatic with commencement of displacement of the bolt from the partially retracted position to the fully projected position.

The bolt, as in ordinary door locks, may be 30 longitudinally displaced by the operation of an angularly displaceable handle said displacement in the locking direction being assisted by a spring and being resisted in the opposite direction 35 thereby.

The invention is more particularly described with reference to the accompanying drawings, in which:

Figure 1 is a view in elevation of one form of 40 door lock.

Figure 2 is a corresponding sectional plan view but showing a safety catch associated with the door lock of Figure 1.

Figure 3 is a plan view partly in section of 45 the operative end of a modified form of door lock when the door is approaching the closed position.

Figure 4 is a corresponding sectional plan of 50 a lock according to Figure 3 but when the door is partially closed but locked to prevent retraction without the operation of the lock handle.

Figure 5 is a corresponding sectional plan view but with the door in its fully closed and locked position.

Figure 6 is an elevation of a further modified 55 form of construction.

Figure 7 is a corresponding plan view partly in section.

Figure 8 is a sectional plan of the operative end of a door lock of a still further modified form of construction with the door in a partially 5 closed but locked position incapable of retraction without operating the handle of the lock.

Figure 9 is a corresponding sectional plan view of the operative end of the door lock of Figure 8 but with the door in its fully closed and locked 10 position.

Figure 10 is an end view of the bolt of Figure 9.

In the construction according to Figures 1 and 2 the lock has a base plate 20 forming a part of the lock casing, which base plate carries a fixed 15 guide 21 for a sliding bolt 22 which is provided with ribs 23, 24, 25, on its rear face. A spring 26 is anchored at 27 to the base plate 20 and its opposite end extends into the space between the ribs 24, 25, of the bolt and between the rear 20 face of the bolt and the base plate 20, the effect of this spring being to force the bolt towards its locked position.

A cam 28 is carried by an operating member 29 which has a rectangular bore 30 therein for 25 the reception of the spindle of the lock handle. The operating member 29 is of circular external periphery and is mounted for rotation within a circular bore 31 of the guide member 21 so that on angular displacement of the lock handle 30 about its spindle the cam 28 is angularly displaced relatively to the base plate 20. In said angular displacement the part 32 of the cam is adapted to engage with the rib 23 of the bolt to force this in a retracted direction.

A rubber pad 33 is carried by the base plate 20 and is seated against a rib 34 of said base plate, said rubber pad being engaged by the rib 24 of the bolt when the latter is released to take up its locking position under the action of the spring 40 26. The provision of this rubber buffer 33 thus ensures silence of operation during locking.

A trip member consisting of a lever 35 is pivotally mounted at 36 to the outer face of the plate member 20. In the normal position of this trip member 45 one arm 35a is adapted to pass through a slot 36a in the base plate 20 whilst the other arm 35b on pivotal closing movement of the door is adapted ultimately to come into contact with a projection 37 of a catch 38 on the door frame. The pivotal member 35 is normally maintained in the position shown in Figure 2 by a spring 39.

The catch on the door frame has a recess 40, the locking face of the catch being shown at 41. In the fully closed position of the door this 55

locking face 41 of the catch is engaged by a locking face 42 on an enlarged head 22a of the bolt. This locking face 42 of the bolt may be uniplanar or again it may be slightly tapered or notched.

In operation, in order to open the door the handle is turned in an anticlockwise direction whereupon the bolt 22 is moved against the spring from the position shown in chain dotted lines in Figure 1 to the position shown in full lines in Figures 1 and 2. Immediately the rib 23 passes to the left of the end of the arm 35a of the lever 35 the latter, under the action of the spring 39 takes up the position shown in Figure 2 of the drawings so that on release of the handle the bolt is prevented from returning to its locked position.

In this position the spring 26 merely functions to retain the rib 23 in contact with the arm 35 of the trip mechanism and is consistent with the position in which the bolt is neither fully retracted nor in the locked state but is intermediate the two positions. When it is desired to close the door then a push is exerted on the door or the handle without rotating the latter and the door is angularly displaced towards the frame until the free end 35b of the trip lever comes into contact with the projection 37, whereupon the lever 35 is angularly displaced about its pivot 36 to take up a position substantially parallel with the base plate 20 thus enabling the bolt to be longitudinally displaced into the locked position with the enlarged head 22a of the bolt within in the recess 40 and the face 42 of the bolt in contact with the face 41 of the catch.

In order to prevent unauthorised opening of the door when closed a lever 43 pivotally mounted on the base plate at 44 and normally retained in the position shown in Figure 1 by a spring 45 is adapted on operation by a key to be angularly displaced about the pivot 44 to bring the free end 46 of the lever within a notch 47 in the cam member 28 thereby preventing movement of the cam member in an anticlockwise direction on manual operation of the handle.

In the modified form of construction shown in Figures 3—5 the enlarged end 22a of the bolt carries a spring controlled tongue 48 which has a spherical end 49 to enable it to be angularly displaced within a complementary recess in the bolt head. A spring 50 is adapted to hold the tongue normally in the position shown in Figure 3.

The frame 51 of the door has secured thereto a catch 52 which has a pair of shoulders 53, 54, adapted for engagement by the tongue 48. In this construction, on closing the door the tongue 48 rides over a face 55 of the catch while the bolt 22 is held by the trip member 35. On nearing the closed position with the door only slightly ajar the tongue 48 comes into engagement with the shoulder 53 as shown in Figure 4, and in this position the door is partially closed but locked in that it cannot be retracted without operation of the handle to withdraw the bolt to a position in which the rib 23 on the bolt abuts against the rib 34 on the base plate 20. In this position, the tongue 48 is clear of the shoulder 53, as indicated by the dotted line position of the tongue in Figure 5, so that the door may be opened. Thus, opening of the door is effected by further retraction of the bolt beyond its partially retracted position. On further closing of the door, that is to say when the bolt member has reached a position slightly inwardly of the shoulder 54 on the catch, the trip member 35 is released to permit the bolt to slide forward under the action

of the spring 26, whereupon the spring 50 is compressed and the bolt and tongue take up the position shown in Figure 5.

The construction according to Figures 6 and 7 includes a modified form of trip mechanism. In this case a spindle 56 passing through the base plate 20 has at one end an arm 57 extending at right angles to the spindle, the inner face of the depending portion of the arm 57 being curved at 58. The opposite end of the spindle 56 carries a buffer 59 between which and the base plate 20 a spring 60 is located. The head 22a of the bolt is notched at 61 and its locking face is tapered at 62. In this construction also the catch on the door frame is modified in that the safety catch 63 spring controlled at 64 is provided in the frame in advance of the recess 40.

On operation of the handle to open the door the bolt is displaced towards its retracted position to such an extent that on release of the handle the lower end of the arm 57 engages within the notch 61 of the bolt head. This is assisted by the action of the spring 60 which tends to force the buffer 59 away from the base plate 20 and thus pull the arm 57 into the notch 61. On closing the door without operation of the handle the head 22a first of all depresses the safety catch 63 against a spring 64 and having passed the catch permits its release so that the door when partially closed is prevented from retraction without operation of the handle. On further closing movement the spring 60 is compressed by engagement of the buffer 59 with the projection 37 to release the arm 57 from engagement within the notch 61 of the bolt, whereupon the bolt under the action of the spring 26 enters the recess 40 of the door catch. The safety catch 63 of Figure 7 may be used with the bolt construction shown in Figures 1 and 2. For purposes of illustration, the safety catch 63 is shown in Figure 2.

In the further modified form of construction illustrated in Figures 8—10 a trip member of the type shown in Figures 1—5 is utilized whilst the door frame carries a catch which has two locking faces 41, 65. In this construction the bolt head itself carries an auxiliary bolt member or safety catch 66 which has a shoulder 67 thereon between which and a bracket 68 on the bolt 22 is located a spring 69 which exerts a lesser force against the catch 66 than the spring 26 exerts against the bolt 22 so that the catch 66 may be shifted independently of the bolt when it comes into engagement with the locking faces.

In this construction during closing of the door the bolt 22 when retained by the trip is adapted to pass clear of the outer edges of the shoulders or locking faces 41, 65 of the catch on the frame but the auxiliary bolt or safety catch 66 is permitted displacement under the action of the spring 69. Accordingly, on approaching the locking position the catch 66 in the bolt head first engages with the locking face 65 of the catch of the door frame as shown in Figure 8 and in this position the door is partially closed but locked, that is to say, it is prevented from retraction until the handle is operated. On completion of the closing movement, that is to say, by the time the locking face of the bolt 22 has come into alignment with the locking face 41 of the door catch, the trip member 35 is operated to release the bolt so that this takes up the position shown in Figure 9 in which the door is both fully closed and locked. In order to open the door from the position shown in Figure 8, it is simply necessary to further retract the bolt by operation of the

handle so that the catch 66 will clear the shoulder 65 on the door frame.

It is to be clearly understood that various changes in the details of construction and arrangement of parts may be made without departing from the scope of the invention as set forth in the appended claims.

I declare that what I claim is:

1. In a lock for doors, pivotally mounted for angular displacement relatively to door frames the provision of a bolt, resilient means urging said bolt towards its projected position, a trip member, a manually operated handle for retracting said bolt against said resilient means, resilient means urging said trip member into engagement with said bolt to interrupt the movement of said bolt from its retracted to its projected position until automatic release of said trip member is effected during final closing movement of said door, and a safety catch member slidably mounted on said bolt to project therefrom for engagement by said frame during retention of said bolt by said trip member when said door approaches

the plane of said frame prior to locking, to prevent withdrawal of said door relatively to said frame except on operation of said handle.

2. A lock for doors comprising a bolt, resilient means for resisting the displacement of said bolt in the retracting direction, means for retracting said bolt in opposition to said resilient means, a resilient pressed trip member disposed in the path of movement of said bolt for maintaining said bolt in partially retracted position until released during final closing movement of the door, a safety catch carried by said bolt and having limited movement independent of said bolt and adapted to cooperate with a portion of the door frame for preventing opening of the door when said bolt is maintained in its partially retracted position except by operation of said retracting means, and spring means operating against said safety catch for normally urging the same to a position for cooperation with the frame.

20
